MACHINE FOR PRESSING SOLES ON THE
BOTTOMS OF SHOESSidney J. Finn, Beverly, Mass., assignor to United
Shoe Machinery Corporation, Paterson, N. J.,
a corporation of New Jersey

Application October 4, 1937, Serial No. 167,171

29 Claims. (Cl. 12—36)

This invention relates to machines for use in the manufacture of shoes for pressing soles on the bottoms of shoes. The invention is herein illustrated as embodied in a sole laying machine of the type in which shoe supporting means and a sole laying member or pad shaped to conform substantially to the contour of the bottom of a shoe are relatively movable to press the sole and shoe together, but it is to be understood that in various 5 novel aspects the invention is not limited to machines for performing sole laying operations.

In one important aspect the invention provides a novel construction and arrangement of means for positioning shoes of different sizes in substantially the same relation lengthwise and widthwise of the shoe to the sole pressing means and for determining the lengthwise position of an unattached sole with respect to the bottom of the shoe, and means for positioning the sole at the forepart laterally of the sole pressing means. In 10 the machine herein shown the arrangement is such that the positions of the shoe and sole are determined when the shoe supporting means is in a shoe receiving position by devices that are movable into shoe and sole engaging positions by movement of a single controlling member further movement of which starts power-operated means that moves the supporting means to a position opposite to the sole pressing pad and thereafter effects relative movement of the supporting means 15 and the pad to press the sole and shoe together after they have been thus positioned. For determining the positions of the shoe and sole the machine herein shown has a pair of devices for engaging the shoe at its toe and heel ends, the heel-end engaging device being shaped to embrace the heel end of the shoe and to position it in that location in proper relation widthwise of the shoe to the sole pressing pad and the toe end engaging device having formed thereon an abutment for 20 determining the lengthwise position of an unattached sole with respect to the shoe bottom, and separate pairs of devices for engaging the shoe and sole respectively at the opposite sides at the forepart to centralize the shoe and sole laterally of the pressing pad. Preferably and as illustrated, the construction is such that with the shoe supporting means in position opposite to the pressing pad each shoe is located by the toe and heel 25 end engaging devices with the junction of its forepart and shank portions substantially in alignment with the junction of the forepart and shank pressing portions of the pressing pad, thus insuring best results in the laying of soles by the use of a shaped pad.

In the machine herein shown the shoe and last are supported bottom upward for the sole laying operation by a toe support which is arranged to engage the top of the forepart of the shoe and a heel-end support for engaging the top of the cone of the last. The toe and heel-end supports are movable lengthwise of the shoe to accommodate 5 shoes of different sizes and are also mounted for swinging movement heightwise of the shoe to vary their relative positions for shoes of different sizes. 10 In accordance with one feature of the invention there is provided mechanism operative in response to movement of the toe and heel-end engaging devices into shoe engaging positions for moving the toe and heel-end supports into positions to engage each shoe and last in substantially 15 the same relation lengthwise of the shoe, additional mechanism being provided in accordance with a further feature of the invention for varying the relative heightwise positions of the toe and heel-end supports in accordance with 20 variations in thickness between the foreparts and the heel ends of lasts of different sizes to cause each last to be positioned with its bottom face at the toe and heel ends in substantially the same 25 heightwise relation to the sole pressing pad.

In accordance with another feature of the invention there is provided novel means acting through the pressing pad in the sole pressing operation to apply different pressures to different 30 portions of the sole. The pressing pad is preferably made of flexible material, such as rubber, molded approximately to conform to the contour of the bottom of a shoe and, as herein illustrated, is supported by a flexible container having separate fluid-filled chambers separated by a rib extending laterally of the shoe and located substantially at the junction of the forepart and shank pressing portions of the pressing pad. As herein 35 shown, means is provided for confining the flexible container constructed to expose a portion of one wall of each of the fluid-filled chambers of the container, and engaging the exposed portions of the walls of the chambers are plungers which are acted upon by separate spring means to apply 40 different pressures through the fluid-filled chambers to the forepart and shank pressing portions 45 of the pressing pad in the pressing operation.

The above and other features of the invention, including novel means for locking the positioning 50 devices in shoe and sole-engaging positions and various novel details of construction and combinations of parts will now be more particularly described by reference to the accompanying drawings and thereafter pointed out in the claims.

- In the drawings,
- Fig. 1 is a view in front elevation of a machine in which the invention is embodied, with a portion of the structure broken away;
- 5 Fig. 2 is a view partly in left-hand side elevation and partly in section of the machine shown in Fig. 1, with parts broken away;
- Fig. 3 is a detail plan view illustrating the positioning of a shoe and sole by the shoe and sole 10 engaging devices of the machine;
- Fig. 4 is a view on an enlarged scale of the lower portion of the structure shown in Fig. 2, partly in elevation and partly in section;
- 15 Fig. 5 is a plan view of the mechanism shown in Fig. 4;
- Fig. 6 is a view in side elevation on an enlarged scale of the upper portion of the shoe supporting jack with the parts in the positions that they assume before the jacking operation;
- 20 Fig. 7 is a view similar to Fig. 6 illustrating the positions of the parts after the jacking operation;
- Fig. 8 is a section on the line VIII—VIII of Fig. 6;
- 25 Fig. 9 is a view similar to Fig. 8 with the parts in shoe and sole engaging positions;
- Fig. 10 is an enlarged view partly in front elevation and partly in section of the upper portion of the machine shown in Fig. 1, illustrating more 30 fully the mounting of the pressing pads;
- Fig. 11 is a sectional view showing a portion of the mechanism for operating the gaging devices for locating the shoe and sole laterally of the sole pressing pad;
- 35 Fig. 12 is a section on the line XII—XII of Fig. 7;
- Fig. 13 is a perspective view of parts shown in Fig. 11;
- 40 Figs. 14 and 15 are detail view of portions of the mechanism for operating the shoe and sole gaging devices;
- Fig. 16 shows partly in plan and partly in section the means for locking the gaging devices in shoe and sole engaging positions;
- 45 Fig. 17 is a perspective view of a portion of the mechanism for operating the gaging devices for locating the shoe lengthwise of the pressing pad; and
- 50 Fig. 18 is a vertical section laterally of the machine through the pressing pads and their supporting means and illustrating the mechanism for applying pressure to the forepart engaging portions of the pads.
- The machine herein shown is a twin machine having two sets of instrumentalities arranged 55 side by side for operating respectively on shoes in different locations in the machine. As illustrated, each of the two sets of instrumentalities comprises sole pressing means and a shoe support or jack that is movable from a shoe and last 60 receiving position rearwardly to a position opposite to the sole pressing means and is movable thereafter relatively to the sole pressing means to press the sole and shoe together. Separate mechanisms that are substantial duplicates of 65 each other are provided for operating the two sets alternately, whereby one shoe is subjected to pressure simultaneously with the release from pressure of another shoe previously operated upon. Since the two sets of instrumentalities are 70 constructed substantially alike except that they are used to operate respectively on right and left shoes, the present description will be confined, for the most part, to that set and its operating mechanism which is at the left-hand side of the machine.
- 75 The illustrated machine is provided with a base 20 having upwardly extending side portions 22 which support, near their upper ends, a pad box 24 (Figs. 1, 2 and 10) in which there are mounted side by side the sole pressing means of the two sets of instrumentalities. The pad box is separated longitudinally by a central rib 26 (Figs. 10 and 18) to form two rectangularly shaped hollow recesses in each of which is mounted an elastic pad 28 of rubber or other suitable material shaped 5 to conform substantially to the contour of the bottom of a shoe, and a flexible container or pad 30 having two liquid filled chambers 32, 34 (Fig. 2) for supporting the forepart and the shank and heel-end portions, respectively, of the pad 28. 10 The chambers 32, 34 are separated by a rib 36 extending laterally of the shoe and located substantially at the junction of the forepart and shank pressing portions of the pad 28. The rib 36 and the walls of the pad 30 are of a rubber composition reinforced by one or more layers of canvas or other suitable fabric. The pads 28 and 30 are held in place in the pad box by clamps 38 fastened to the pad box by screws 40 and extending inwardly to engage the ends of the pad 28 15 beyond that portion that is engaged by the sole of the shoe. For closing the top side of the pad box 24 to confine the pads 30 there is provided a cover plate 42 secured to the side portions 22 of the frame by screws 44. The cover plate 42 is 20 provided with recesses 45 and 47 for exposing a portion of each of the upper walls 50, 52 of the chambers 30, 32 and slidably mounted in these recesses are plungers 46, 48 for engaging respectively the exposed portions of the walls 50, 52. 25 Pivotally connected to the cover plate 42 are arms 54, 56 engaging, respectively, near their pivotal connections to the cover plate upwardly extending stems 58, 60 formed on the plungers 46, 48. Pivotally connected to the outer ends of the arms 40 54 are rods 62 (Fig. 18), and to the outer ends of the arms 56 are rods 64 (Fig. 10), these rods extending downwardly through enlarged openings in bosses 66 on the side portions 22. The rods 62, 64 are surrounded respectively by comparatively long springs 67, 68, each of which engages at its upper end the boss 66 and is supported at its lower end by a washer 70 and a nut and locknut 72 threaded on the lower end of the rod. It will be evident that as the shoe 50 support is moved relatively to the pad 28 to bring the sole of a shoe on the support into engagement with the pad and to apply pressure to the sole, the springs 67 and 68 tend to hold the plungers 46 and 48 against upward movement in response 55 to pressure of the shoe on the pad. The springs 67 and 68 are of different capacities to cause different pressures to be applied through each pad 28 to different portions of the sole, the springs 68 being preferably heavier than the springs 67 so 60 that greater pressure is applied to the shank portions of the sole than to the forepart. It will be evident also that by adjustment of the nut and locknuts 72 the initial pressures applied to different portions of the sole can be varied relatively at will. Preferably also, and as illustrated, the springs 67 and 68 are sufficiently long so that their lengths may be varied by such comparatively small movements as may be imparted to the plungers 46 and 48 as the pad 28 conforms itself 65 more closely to the contour of the shoe bottom without increasing substantially the initial pull of the springs on the arms 54, 56. Thus substantially the same pressure is applied through each pad 28 per unit of area to the forepart and to 70 75

the shank and heel-end portions of the soles of shoes of different sizes and styles.

The shoe support or jack of each set of instrumentalities comprises a toe support or rest 74 for engaging the top of the forepart of the shoe and a heel support 76 for engaging the top of the cone of the last (Figs. 2, 6 and 7). The toe rest 74 comprises a rubber roll 78 mounted to rotate freely on a stud 80 supported by the upwardly extending arms of a bifurcated member 82 which is mounted on a slide 84 for adjustment heightwise of the shoe and is held in adjusted position by a binding screw 86. The heel support 76 is mounted on a second slide 88 for adjustment heightwise of the shoe, a binding stud 90 being provided for holding it in adjusted position (Figs. 6 and 7). The slides 84 and 88 are movable in directions lengthwise of the shoe on a bar 92 that is pivotally connected at 94 adjacent to the toe end of the shoe to an upwardly extending arm 96 on a holder 98 that is movable in directions heightwise of the shoe in guideways formed in a carrier 100 which is pivotally connected at 102 (Figs. 2 and 4) to the base 20 and in the power operation of the machine is swung from a forwardly inclined position rearwardly to a substantially vertical position to carry the shoe support from a shoe and last receiving position to a position opposite to the sole-pressing pad 28. Mounted for movement in directions lengthwise of the shoe on guideways formed on the upper end of the holder 98 is a short slide 104 (Figs. 6 and 7) for supporting the opposite end of the bar 92.

The illustrated machine is provided with means for positioning each shoe on the supporting means in proper lengthwise and widthwise relation to the sole-pressing means, comprising devices for engaging the toe end and the heel end of the shoe and other devices for engaging the opposite sides of the shoe at the ball of the shoe. The devices for engaging the toe end and the heel end of the shoe, indicated generally at 106 and 108 (Figs. 6 and 7), are mounted respectively on upwardly extending arms 110, 112 of bell-crank levers 114, 116 that are pivotally connected to the carrier 100 for swinging movements about axes extending laterally of the shoe and located equal distances at opposite sides of the axis 102 of the carrier 100. In the machine herein shown, swinging movements of equal extent but in opposite directions are imparted to the bell-crank levers 114, 116 by means hereinafter described, to move the devices 106 and 108 toward each other into engagement with the toe end and the heel end of the shoe. When the carrier 100 has been swung into a substantially vertical position each shoe is thus centralized with respect to the axis of the carrier which is so located lengthwise of the shoe relatively to the sole pressing pad 28 that each shoe is located in proper lengthwise relation to the pad, that is, with the junction of its forepart and shank portions substantially opposite the junction of the forepart and shank pressing portions of the pad 28. The device 106 comprises a slide 118 that is movable lengthwise of the arm 110 in a guideway formed in the arm and is upheld by a spring 120 with the reduced end portion of a screw 122 carried by the arm in engagement with the slide at the lower end of a slot 124 formed in the slide. Fast on the slide 118 is a block 126 for engaging the toe end face of the shoe and a forwardly extending plate 128 for engaging the top of the toe end of the shoe. The device 108 comprises a substantially V-shaped

member 130 pivotally connected to the arm 112 at its upper end and arranged to engage the shoe at the opposite sides of its heel end. The member 130 is held against swinging movement relatively to the arm 112 in position to embrace the heel end of the shoe by means of a spring-pressed plunger 131 in the arm 112 engaging a recess 133 in the member 130.

The bell-crank levers 114, 116 are provided respectively with inwardly extending arms 132, 134 of equal lengths and connected to the arms are equal links 136 that are pivotally connected together and to the upper end of a rod 138 by means of a pivot pin 140 carried by a short slide 141 (Fig. 17) mounted in a guideway in the carrier 100. The lower end portion of the rod 138 is surrounded by a sleeve 142 (Fig. 15) that is bored centrally to receive the rod and also an upwardly extending rod 144 pivotally connected by means of a pivot pin 146 to a treadle 148 that is pivotally connected at 150 to the base 20 (Figs. 2 and 4). Surrounding the sleeve 142 and connected at one end to the pivot pin 140 and at the other end to the pivot pin 146 is a tension spring 152 which tends to hold the two rods 138, 144 in engagement with each other when the parts are in the positions shown in Fig. 2 with the treadle 148 in its uppermost position determined by engagement of an adjustable stop, illustrated as a screw 154, carried by the treadle with a portion of the base 20. A spring 156 connected at one end to the treadle and at the other end to the base 20 tends to swing the treadle in a direction to hold the stop 154 in engagement with the base. Depression of the treadle 148 acts through the spring 152 and the links 136 to swing the bell-crank levers 114 and 116 in directions to move the devices 106, 108 toward each other to clamp the shoe and last therebetween, the spring 120 yielding to permit the device 106 to adjust itself relatively to the arm 110 of the bell-crank lever 114 with the plate 128 in engagement with the top of the toe end of the shoe and the block 126 engaging the toe end face of the shoe.

The devices for engaging the opposite sides of the shoe at the ball of the shoe comprise upwardly extending arms 158, 160 (Figs. 8 and 9) that are substantially the same length and are pivotally connected, respectively, at 162, 164 to outwardly extending ears 166 on the carrier 100. The arms 158, 160 are provided respectively with downwardly extending portions 168, 170 of equal lengths that are connected by equal links 172 to a short slide 174 movable heightwise of the shoe in a guideway 176 formed in the carrier 100 (Fig. 16). A spring 178 connected at one end to a pin 180 which projects from the slide 174 and forms the pivot for the links 172 and, at the other end, to a pin 182 projecting from a second slide 184 mounted in the guideway 176, tends to hold the slide 174 in engagement with an abutment 175 on the slide 184 (Figs. 11 and 13). The slides 174 and 184 are free to move relatively to each other in the guideway 176 and are held in the guideway by a cover plate 185 that extends across the lower portion of the guideway and is secured to the carrier by screws 187 (Fig. 2). Pivotally connected to the lower end of the slide 184 by a pivot pin 186 is a rod 188 slidable in a bushing 190 into which extends a rod 192 (Fig. 14) pivotally connected by means of a pivot pin 194 to the treadle 148. A spring 196 surrounds the bushing 190 and is connected at its upper end to the pin 186 and at its lower end to the pin 194. When the treadle 148 is in its uppermost position the two rods 188, 75

192 are held in engagement with each other by the spring 196 with the arms 158, 160 in their outermost positions, as shown in Fig. 8. It will be evident that, as the treadle 148 is depressed to move the devices 106, 108 into engagement with the toe and heel ends of the shoe, the arms 158, 160 are swung toward each other into engagement with the shoe at the opposite sides of the ball portion, the construction being such that 10 the forepart of the shoe is thus centralized with respect to the pressing pad 28.

To assist in positioning the sole accurately with respect to the shoe bottom the illustrated machine is provided with separate devices for engaging the edge of the sole at the toe end and at the opposite sides at the ball of the shoe. For 15 engaging the sole at the opposite sides at the ball of the shoe there are provided upwardly extending arms 198, 200 (Figs. 8 and 9), that are pivotally connected to the carrier 100 for swinging movements toward and from each other about the same axes 162, 164 as the above-mentioned arms 158, 160. Formed on the arms 198, 200 are downwardly extending portions 202, 204 of equal 20 lengths that are connected to the slide 184 by equal links 206. As the slide 184 is moved downwardly by depression of the treadle the arms 198, 200 are swung toward each other into engagement with the edge of the sole to centralize its 25 forepart portion with respect to the shoe bottom and the sole pressing pad 28. By reference to the drawings it will be seen that the downwardly extending portions 202, 204 of the arms 198, 200 are longer than the downwardly extending portions 30 168, 170 of the arms 158, 160 so that the arms 158, 160 complete their inward swinging movements to position the shoe laterally of the pad 28 before the arms 198, 200 have been swung toward each other far enough to engage the opposite edges of the sole, the spring 178 yielding as the slide 184 is moved relatively to the slide 174 to swing the arms 198, 200 into engagement with the opposite edges of the sole in the continued downward movement of the treadle. For 35 engaging the edge of the sole at the toe end to determine the lengthwise position of the sole relatively to the shoe bottom there is secured to the slide 184 a separate contacting member or gage 208.

The lengthwise position of each shoe in the machine, as hereinbefore stated, is determined by engagement of the devices 106 and 108 with the toe end and the heel end of the shoe, these devices being moved toward each other by the 40 swinging of the bell-crank levers 114, 116 about their pivotal connections to the carrier 100 to clamp the last and shoe between them in response to depression of the treadle 148. This arrangement is utilized to effect an adjustment 45 lengthwise of the shoe of the toe rest 74 and heel support 76 to position them for engagement with each shoe and last in substantially the same relation to the shoe. As shown in Figs 6 and 7 the slides 84 and 88 on which the toe rest and heel support are mounted are connected, respectively, by links 212 and 214 to the oppositely extending arms 216 and 218 of a lever 220 mounted to turn on a shouldered stud 222 carried by the bar 92. Pivotal connected to the upper end of the arm 50 75 216 of the lever is a link 224 connected at its opposite end to the upwardly extending arm 110 of the bell-crank lever 114. As the bell-crank lever 114 is swung in a direction to move the device 106 into engagement with the toe end of the shoe a swinging movement in a clockwise di-

rection (Fig. 6) is imparted to the lever 220 to move the slides 84 and 88 toward each other along the bar 92 to adjust the positions of the toe rests 74 and heel supports 76 in accordance with the length of the shoe being operated upon. The 5 lengths of the links 211, 214 and the effective lengths of the arms 216 and 218 for moving the slides 84 and 88 through the links are such that when the devices 106, 108 have been moved into engagement with the toe and heel ends of each shoe the toe rest 74 will have been moved into position to engage the top of the forepart of the shoe at or near the tip line and the heel support 76 will have been moved into a position in which it engages the top of the cone of the 10 last substantially midway between the heel breast line of the shoe and the heel-end face of the last.

In the illustrated construction, the slide 104 for supporting the free end of the pivoted bar 92 has 20 a forwardly and upwardly inclined face 226 arranged to be engaged by a rounded projection 228 on the bar. The slide 104 is connected to the arm 218 of the lever 220 by a link 230 so that in response to clockwise swinging movement 25 of the lever 220 the slide 104 is moved along the holder 98 toward the toe end of the shoe and by reason of the inclination of its face 226 acts to swing the bar 92 relatively to the holder in a direction to raise the toe rest and heel support. It 30 will be evident that since the bar 92 is pivoted at 92 to the holder 98 adjacent to the toe end of the shoe, as it is thus swung the heel support receives a greater upward movement than the toe rest. Preferably the inclination of the face 35 226 of the slide 104 is such that as movements of different extent are imparted to the devices 106 and 108 to position shoes of different sizes in substantially the same lengthwise relation to the sole pressing means the heightwise positions 40 of the toe rest and heel support are varied in accordance with variations in thickness between the foreparts and the heel ends of lasts of different sizes so that the bottom face of each last at the toe and heel ends will be positioned at substantially 45 the same height irrespective of the size of the last.

For imparting to each carrier 100 its rearward swinging movement there is provided an arm 232 (Fig. 4) pivotally connected at 234 to the 50 base 20 of the machine and carried by this arm is a cam roll 236 arranged to engage a path cam 238 formed in one face of a cam wheel 240 fast to a shaft 242 extending laterally of the machine and mounted to turn in suitable bearings in the 55 base 20. At its upper end the arm 232 is connected by a link 244 to the carrier 100. The shape of the cam 238 is such that substantially at the beginning of the power operation of the machine the arm 232 is swung in a direction to 60 swing the carrier from a forwardly inclined position rearwardly to a substantially vertical position beneath the sole pressing pad 28. As the carrier completes its rearward swinging movement the holder 98 and the shoe support are 65 moved upwardly, by means which will presently be described, to bring the sole of a shoe on the support into engagement with the pad 28 and to apply pressure to the sole before the machine comes to rest. In the next operation of the machine the shoe is released from pressure by downward movement of the holder, and the carrier is swung outwardly to its initial position simultaneously with the application of pressure 70 to a shoe by the other twin mechanism of the 75

machine. Upward movement is imparted to the holder 98 by means of a toggle comprising links 245 and 246, the links being pivotally connected together by a pivot stud 248 and the link 244 being connected at its upper end to the holder 98. The link 246 is pivotally connected at its lower end to the carrier 100 and between its ends is connected by a link 250 to an eccentrically mounted stud 252 on the cam wheel 240. Through these connections the eccentric stud 252 acts to straighten the toggle 244, 246 after the cam 238 has swung the arm 232 far enough to the left (Fig. 4) to move the carrier 100 from its forwardly inclined position rearwardly to a substantially vertical position. Straightening of the toggle links 244, 246 acts to raise the holder 98 and the shoe support to bring the sole of a shoe on the support into engagement with the pad 28 and to apply pressure to the sole.

20 The machine is operated by an electric motor 254 (Fig. 5) connected by a belt 256 to a pulley 258 slidably mounted for lengthwise movement on a shaft 260 which extends from the front to the rear of the machine and is supported by suitable bearings in the base 20 and at its rear end by a bracket 262 secured by screws 264 to the base. The pulley 258 is provided with a friction clutch face 266 (Fig. 4) arranged to cooperate with a clutch member 268 fast on the shaft 260.

25 A spring 270 surrounding the shaft 260 between the clutch member 268 and the pulley 258 tends to move the pulley out of engagement with the clutch member and to hold it in engagement with a shoulder 272 on the bracket 262. The hub of the pulley 258 is provided with an annular groove 274 into which extends pins 278 carried by the downwardly extending arms 280 of a pair of bell-crank levers 282 that are pivotally connected at opposite sides of the pulley to an upwardly extending arm 284 of the bracket 262. Each bell-crank lever 282 has a forwardly extending arm 286 connected by a toggle comprising links 288 and 290 to one of the treadles 148 of the twin mechanisms of the machine. The links 288, 290 of each toggle are held in substantially parallel relation by a spring 292 and each link 290 has formed therein a lengthwise slot 294 through which extends a pin 296 carried by its associated treadle. Fast on the shaft 260 is a worm 298 the teeth of which mesh with the teeth of a worm wheel 300 fast to the cam shaft 242.

30 When the operator depresses the treadle 148 associated with that set of instrumentalities the shoe support of which is in shoe and last receiving position, the pin 296 is moved upwardly into engagement with the link 290 at the upper end of the slot 294 and since the toggle links 288, 290 are in substantially parallel relation at this time the bell-crank lever 282 is swung in a direction to move the pulley 258 against the resistance of the spring 270 along the shaft 260 and into engagement with the clutch member 268 to start the operation of the machine. For stopping the machine with a shoe under pressure there is provided a roll 302 (Figs. 4 and 5) carried by the cam wheel 240 and arranged to engage a forwardly extending finger 304 on the toggle link 288 and to swing the toggle links 288, 290 into non-parallel relation, thereby releasing the pulley 258 to the action of the spring 270 for movement out of engagement with the clutch member 268. It is at this time in the cycle when the treadle is released by the operator. It will be understood that the finger 304 is thus engaged by the roll 302 after the carrier 100 has completed its rearward

5 swinging movement and the toggle links 244, 246 have been moved into parallel relation to raise the shoe support to press the sole of a shoe on the support against the pad 28. It will be understood also that as the carrier 100 of one set of instrumentalities is swung rearwardly and the toggle links 244, 246 are moved into substantially parallel relation to raise the holder 98 and the shoe support of that set, the toggle links 244, 246 of the other set are moved into non-parallel relation and the carrier 100 of the other set is swung outwardly to its initial position, the cam 238, the eccentric stud 252, and the roll 302 on one cam wheel 240, being spaced apart 180° from the corresponding parts on the other cam wheel so that the shaft 242 is automatically disconnected from the drive pulley 258 at the end of each half revolution of the shaft with a shoe under pressure in one half of the machine and the shoe support of the other half in a shoe and last receiving position.

10 As previously pointed out, after the carrier 100 has been swung from its forwardly inclined position rearwardly to a substantially vertical position beneath the pressing pad 28 the holder 98 is moved upwardly by the straightening of the toggle links 244, 246 to bring the sole of a shoe on the supporting means into engagement with the pad 28 and to apply pressure to the sole. As the holder is moved upwardly the shoe and sole are moved out of engagement with the devices for locating the shoe and sole in proper lengthwise and widthwise relation to the pad 28 and to each other. As the shoe and sole are thus moved out of engagement with the gaging devices the springs 35 152, 178 and 196 tend to swing the devices farther inward toward each other and in order to avoid any interference between these devices and the shoe and sole as the shoe is released from pressure by the downward movement of the holder 98 in the next operation of the machine there is provided means for locking the shoe and sole engaging devices frictionally in shoe and sole engaging positions until after the holder has completed its downward movement to return the shoe supporting means to its initial position. This means comprises friction devices illustrated as spring-pressed plungers 306, 308 (Fig. 16) 40 slidably mounted in recesses 310 in a support 312 secured to a rib 314 extending laterally of the machine between the upwardly extending portions 22 of the base 20. Within the recesses 310 the plungers 306, 308 are surrounded by springs 316 which act on the plungers to hold them with pins 318 carried by the plungers in engagement 45 with the rear face 320 of the support 312. In the rearward movement of the carrier 100, the plungers 306 and 308 are moved relatively to the support 312 against the resistance of the springs 316 by engagement respectively with the slide 184 and a pin 322 in the carrier 100, which pin serves as an extension of the plunger 308 in engagement with the slide 141. The pin 322 is slidably mounted in the carrier and is provided with a lengthwise slot into which extends a locking pin 60 324 fast in the carrier (Fig. 17). As the carrier 100 completes its movement into position beneath the pad 28 the spring-pressed plunger 306 acts to press the slide 184 hard against the slide 174 and the spring-pressed plunger 308 acts to press 70 the pin 314 hard against the slide 141. It will be evident that with the slides 141, 174 and 184 held frictionally against movement relatively to the carrier the devices 106 and 108 and the arms 158, 160 and 198, 200 are held substantially in 75

shoe and sole engaging positions until after the shoe supporting means has been lowered by downward movement of the holder 98 and the carrier has been swung far enough forwardly to move the slide 184 and the pin 314 out of engagement with the plungers 306 and 308. It will be understood that the operator will have released the treadle after the toggle links 245 and 246 have been moved into parallel and the pulley 258 has been released to the action of the spring 270 for movement out of engagement with the clutch member 268 so that the springs 152 and 196 and the spring 156 will have moved the treadle upwardly far enough to bring the rods 144 and 192 into abutting relation to the rods 138 and 188. Thereafter, when the slides 141, 174 and 184 are released for movement relatively to the carrier, as above described, the spring 156 acts to swing the treadle farther upwardly to its initial position. As the treadle is thus swung it acts through the rods 144 and 138, slide 141 and levers 114, 116 to move the devices 106 and 108 away from each other into the positions shown in Fig. 6 and through the rods 192, 188 and slide 184 to swing the arms 158 and 160 into the positions shown in Fig. 8, the arms 198, 200 being also swung outwardly to their initial positions in the upward movement of the slide 184 by engagement of the abutment 175 on the slide 184 with the slide 174. It will be evident that with the slide 141 locked against movement relatively to the carrier 100 to hold the device 106 in shoe engaging position, no movement out of adjusted positions will be imparted to the toe rest 74 and heel support 76 during the relative movements of the holder 98 and the pad 28 to apply pressure to the shoe and to release the pressure except such slight movement as there may be imparted to the toe rest and heel support due to the rocking of the lever 220 about its pivot 222 by reason of the swinging of the link 224 relatively to the arm 110. The arrangement of the parts is such, however, that as the holder 98 is moved upwardly to bring the sole of the shoe on the supporting means into engagement with the pad 28 and to apply pressure to the sole the pivotal connection between the link 224 and the lever 220 will be moved substantially the same distance from a position below the pivotal connection of the link 50 to the arm 110 to a position above that pivotal connection so that the toe rest 74 and heel support 76 at the end of the upward movement of the holder 98 will be in substantially the positions determined by the engagement of the device 106 55 with the toe end of the shoe.

In the operation of the machine, briefly summarized, the operator will place a shoe and last on that support which is in its outermost position and by depression of the appropriate treadle 148 60 will move the devices 106 and 108 into engagement with the toe end and the heel end of the shoe to position the shoe in predetermined lengthwise relation to the pad 28 and will move the devices 158, 160 into engagement with the shoe at the opposite sides of the ball of the shoe to position the shoe laterally of the pad. As the devices 106 and 108 are moved into positions to engage the toe and heel ends of the shoe the toe rest 74 and the heel support 76 in response to the swinging of the lever 220 are adjusted lengthwise of the last into positions to engage the top of the forepart of the shoe at or near the tip line and the top of the cone of the last substantially 70 midway between the heel breast line and the

heel-end face of the last and are also adjusted heightwise of the last to position the last with its bottom face in predetermined heightwise relation to the holder 98. The operator will then take a sole of the correct size, one face of which has been previously coated with an adhesive, whether a right or a left, from a rack A which, as illustrated, is mounted on the cover plate 42 within easy reach of the operator's hand, and will place the sole on the bottom of the shoe with the adhesive coated face of the sole in engagement with the bottom of the shoe at the forepart and the edge face of the sole at the toe end against the gage 208 and by further downward movement of the treadle will swing the devices 198, 200 15 into engagement with the edge of the sole at the opposite sides at the ball of the shoe to position the sole laterally of the pad 28 and the shoe. The operator will then press the sole against the bottom of the forepart and shank portions of the shoe to cause it to adhere thereto, after which, by further depression of the treadle 148, the pin 296 is moved into engagement with the link 290 at the upper end of the slot 294 to move the driving pulley 258 into engagement with the clutch member 268 to start the operation of the machine. Substantially at the beginning of the operation of the machine the carrier 100 at that side at which the operator is working is swung from a forwardly inclined position rearwardly to 30 a substantially vertical position to position the shoe and last opposite to the sole pressing pad 28 with the junction of the forepart and shank portions of the shoe and sole substantially in alignment with the junction of the forepart and shank pressing portions of the pad 28, and the holder 98 and the shoe support are raised to bring the sole of the shoe on the support into engagement with the pad 28 and to apply pressure to the sole. As the shoe support is raised the shoe 40 and sole are moved out of engagement with the devices 106 and 108 and the arms 158, 160 and 198, 200, which as previously described are held against movement out of shoe and sole engaging positions by the locking of the slides 141, 174 and 45 184, and substantially at the time when the toggle links 244, 246 have been moved into substantially parallel relation the finger 304 is engaged by the roll 302 to move the toggle links 288 and 290 into non-parallel relation and thereby to release the 50 driving pulley 258 to the action of the spring 270 to stop the operation of the machine with the shoe under pressure. When the machine is next started the holder 98 and the shoe support are lowered to return the shoe and sole into engagement with the devices 106 and 108 and the arms 158, 160 and 198, 200 after which the carrier 100 55 is swung outwardly to initial position, the slides 141, 174 and 184 being unlocked in the outward movement of the carrier to permit the devices 106 and 108 and the arms 158, 160 and 198, 200 to be returned to their initial positions.

Having described the invention, what I claim as new and desire to secure by Letters Patent of the United States is:

1. In a machine for pressing soles on the bottoms of shoes, the combination with sole pressing means, of means for supporting a shoe and its last bottom upward for the sole pressing operation, means for positioning each shoe and last on said supporting means in substantially the same relation lengthwise and widthwise to said sole pressing means and for determining the lengthwise position of an unattached sole with 70 75

respect to the bottom of the shoe, and separate means for positioning the sole at the forepart laterally of the sole pressing means.

2. In a machine for pressing soles on the bottoms of shoes, the combination with sole pressing means, of means for supporting a shoe and its last bottom upward for the sole pressing operation, means for positioning each shoe and last on said supporting means in substantially the same 10 relation lengthwise and widthwise to said sole pressing means and for determining the lengthwise position of an unattached sole with respect to the bottom of the shoe, means for centralizing the sole at the forepart laterally of the sole pressing means, and means for effecting relative movement of the supporting means and the sole pressing means to press the sole and shoe together after they have been thus positioned.

3. In a machine for pressing soles on the bottoms of shoes, the combination with sole pressing means, of means for supporting a shoe and its last bottom upward for the sole pressing operation, means arranged by engagement with the shoe and an unattached sole to position them in 25 proper relation lengthwise and widthwise to said sole pressing means, and means for moving the supporting means relatively to said positioning means to bring the sole into engagement with the sole pressing means and to press the sole and shoe together after they have been thus positioned.

4. In a machine for pressing soles on the bottoms of shoes, the combination with sole pressing means, of means for clamping a shoe to position 35 it in proper lengthwise and widthwise relation to said sole pressing means, gaging means carried by said clamping means for determining the lengthwise position of an unattached sole with respect to the shoe bottom, separate means for 40 clamping the sole at the opposite sides at the ball of the shoe to position it in that location in proper widthwise relation to the sole pressing means, and shoe supporting means for moving the shoe and sole after they have been thus positioned out of engagement with said clamping means and relatively to said sole pressing means to press the sole and shoe together.

5. In a machine for pressing soles on the bottoms of shoes, the combination with sole pressing means, of means for supporting a shoe and its last bottom upward for the sole pressing operation, devices for engaging the shoe at the toe end and at the heel end, said devices being movable toward each other lengthwise of the shoe to clamp 50 the shoe between them and to position it in proper lengthwise relation to said sole pressing means, an abutment carried by said toe end engaging device for determining the lengthwise position of an unattached sole with respect to the shoe bottom, separate pairs of devices for engaging the shoe and sole respectively at the opposite sides at the ball of the shoe to centralize the shoe and sole laterally of the sole pressing means, and means for moving the supporting means relatively to said devices to bring the sole into engagement with said sole pressing means and to press the sole and shoe together after they have been thus positioned.

6. In a machine for pressing soles on the bottoms of shoes, the combination with sole pressing means, of means for supporting a shoe and its last bottom upward for the sole pressing operation, different pairs of devices movable respectively lengthwise and laterally of the shoe to 75 position it in proper relation to said sole pressing

means by engagement with the shoe at its toe and heel ends and at the opposite sides at the ball of the shoe, an abutment carried by one of said devices for determining the lengthwise position of an unattached sole with respect to the shoe bottom, separate devices for positioning the sole at the forepart laterally of the sole pressing means, means to lock said devices in shoe and sole engaging positions, and means for moving the supporting means relatively to said devices to bring the sole into engagement with said sole pressing means and to press the sole and shoe together after they have been thus positioned.

7. In a machine for pressing soles on the bottoms of shoes, the combination with a pressing pad shaped to conform substantially to the heightwise curvature of the bottom of a shoe, of means for supporting a shoe and its last bottom upward for the sole pressing operation comprising toe and heel-end supports, devices movable toward each other lengthwise of the shoe to clamp the last and shoe between them and to position the shoe in proper relation lengthwise of the shoe to said pressing pad, one of said devices being shaped to embrace the heel end of the shoe and to position it in that location in proper relation widthwise of the shoe to said pressing pad and the other one of said devices having an abutment for engaging the toe end face of the shoe and a separate abutment for determining the position of an unattached sole lengthwise of the shoe bottom, separate pairs of devices for engaging the shoe and sole respectively at the opposite sides at the ball of the shoe to centralize the shoe and sole in that location laterally of the pressing pad, means to lock said devices in shoe and sole engaging positions, and means for effecting relative movement of the toe and heel-end supports and the pad to press the sole and shoe together after they have been thus positioned.

8. In a machine for pressing soles on the bottoms of shoes, the combination with sole pressing means, of devices for engaging a shoe at its toe and heel ends and at the opposite sides at the forepart to position the shoe in proper lengthwise and widthwise relation to said sole pressing means, an abutment carried by one of said devices for determining the lengthwise position of an unattached sole with respect to the bottom of the shoe, separate devices for engaging the sole at the opposite sides at the ball of the shoe to position it in that location laterally of the sole pressing means, means for locking said devices in shoe and sole engaging positions, and means for moving the shoe and sole after they have been thus positioned out of engagement with said devices and relatively to said sole pressing means to press the shoe and sole together and for returning the shoe and sole into engagement with said devices while they remain locked.

9. In a machine for pressing soles on the bottoms of shoes, the combination with sole pressing means, of means for supporting a shoe and its last for the sole pressing operation, said supporting means being movable relatively to said sole pressing means to press the shoe and sole together, a carrier on which said supporting means is mounted, said carrier being movable from a forwardly inclined position rearwardly to move said supporting means from a shoe and last receiving position to a position opposite to said sole pressing means prior to the sole pressing operation, devices mounted on said carrier and arranged by engagement with each shoe at its toe and heel ends and at the opposite sides at the ball

of the shoe to position shoes of different sizes in substantially the same relation lengthwise and widthwise to said sole pressing means, an abutment carried by said toe end engaging device for determining the lengthwise position of an unattached sole with respect to the shoe bottom, separate devices for engaging the sole at the opposite sides at the ball of the shoe to position the sole laterally of the sole pressing means, and means for locking said devices in shoe and sole engaging positions in response to rearward movement of said carrier.

10. In a machine for pressing soles on the bottoms of shoes, the combination with sole pressing means, of means for supporting a shoe and its last for the sole pressing operation, said supporting means being movable relatively to said sole pressing means to press the shoe and sole together, a carrier on which said supporting means is mounted, said carrier being movable from a forwardly inclined position rearwardly into a substantially vertical position prior to the sole pressing operation, devices mounted on said carrier and arranged by engagement with each shoe at its toe and heel ends and at the opposite sides at the ball of the shoe to position shoes of different sizes in substantially the same relation lengthwise and widthwise to said sole pressing means, an abutment carried by said toe end engaging device for determining the lengthwise position of an unattached sole with respect to the shoe bottom, separate devices for engaging the sole at the opposite sides at the ball of the shoe to position the sole laterally of the sole pressing means, an abutment carried by said toe end means, a single controlling member for operating all of said devices, and means for locking said devices against movement out of shoe and sole engaging positions in response to rearward movement of said carrier.

11. In a machine for pressing soles on the bottoms of shoes, the combination with sole pressing means, of means for supporting a shoe and its last bottom upward for the sole pressing operation comprising toe and heel-end supports, a carrier mounted for swinging movement from a forwardly inclined position rearwardly to move said supports from a shoe and last receiving position to a position opposite to said sole pressing means, means on said carrier for determining the proper relation of the shoe and an unattached sole lengthwise and widthwise of the shoe to said sole pressing means comprising members arranged to engage the shoe at its toe and heel ends and at the opposite sides at its forepart and other members arranged to engage the sole at its toe end and at the opposite sides at its forepart, power operated means for imparting to the carrier its rearward swinging movement and for moving the toe and heel-end supports relatively to the sole pressing means to press the sole and shoe together, and a member arranged to be depressed by the operator to move said members into shoe and sole engaging positions and to start said power operated means.

12. In a machine for pressing soles on the bottoms of shoes, the combination with sole pressing means, of means for supporting a shoe and its last bottom upward for the sole pressing operation, a carrier mounted for swinging movement from a forwardly inclined position rearwardly to move said supporting means from a shoe and last receiving position to a position opposite to said sole pressing means, means on said carrier for determining the proper relation of the shoe and an unattached sole lengthwise and widthwise of

the shoe to said sole pressing means comprising members arranged to engage the shoe at its toe and heel ends and at the opposite sides at its forepart and other members arranged to engage the sole at its toe end and at the opposite sides at its forepart, power-operated means for imparting to said carrier its rearward swinging movement and for thereafter effecting relative movement of said supporting means and the sole pressing means to press the shoe and sole together, manually operated means for moving said members into shoe and sole engaging positions and for subsequently starting said power-operated means, and means for locking said members against movement out of shoe and sole engaging positions in response to the rearward swinging movement of said carrier.

13. In a machine for pressing soles on the bottoms of shoes, the combination with sole pressing means, of means for supporting a shoe and its last bottom upward for the sole pressing operation, a carrier mounted for swinging movement from a forwardly inclined position rearwardly to move said supporting means from a shoe and last receiving position to a position opposite to said sole pressing means, power operated means for imparting to the carrier its rearward swinging movement and for thereafter moving the supporting means relatively to the sole pressing means to bring the sole of a shoe on said supporting means into engagement with said sole pressing means and to press the sole and shoe together, means on said carrier for determining the proper relation of the shoe and an unattached sole to said sole pressing means comprising devices for engaging the shoe at its toe and heel ends and at the opposite sides at its forepart and other devices for engaging the sole at the toe end and at the opposite sides at its forepart, and a lever arranged to be swung by the operator to move said devices into shoe and sole engaging positions and movable thereafter to start said power operated means.

14. In a machine for pressing soles on the bottoms of shoes, the combination with sole-pressing means, of means for supporting a shoe and its last at the forepart and the heel end for the sole-pressing operation comprising toe and heel-end supports movable lengthwise of the shoe to accommodate shoes of different sizes, devices movable toward each other lengthwise of the shoe for positioning shoes of different sizes in substantially the same relation lengthwise of the shoe to said sole-pressing means, and mechanism operative in response to such movement of said devices for moving the toe and heel-end supports into positions to engage each shoe and last in substantially the same relation lengthwise of the shoe.

15. In a machine for pressing soles on the bottoms of shoes, the combination with sole-pressing means, of means for supporting a shoe and its last at the forepart and the heel end for the sole-pressing operation comprising toe and heel-end supports adjustable lengthwise of the shoe to accommodate shoes of different sizes, devices arranged by engagement with the toe end and the heel end of the shoe to position it in proper relation lengthwise of the shoe to said sole-pressing means, and mechanism controlled by one of said devices when in shoe-engaging position for determining the adjusted positions of said toe and heel-end supports.

16. In a machine for pressing soles on the bottoms of shoes, the combination with sole-pressing means, of means for supporting a shoe and its

last at the forepart and the heel end for the sole-pressing operation comprising toe and heel-end supports adjustable lengthwise of the shoe to accommodate shoes of different sizes, devices movable toward each other lengthwise of the shoe and arranged by engagement with the toe end and the heel end of each shoe to position shoes of different sizes in substantially the same relation lengthwise of the shoe to said sole-pressing means, and mechanism operative in response to such movement of said devices for adjusting the toe and heel-end supports, said mechanism being constructed to determine the adjusted positions of the supports in accordance with the length of the shoe being operated upon.

17. In a machine for pressing soles on the bottoms of shoes, the combination with sole-pressing means, of means for supporting a shoe and its last at the forepart and the heel end for the sole-pressing operation comprising toe and heel-end supports adjustable lengthwise of the shoe to accommodate shoes of different sizes, shoe clamping means comprising devices for engaging each shoe at its toe and heel ends, mechanism for imparting to said devices equal movements in opposite directions to cause shoes of different sizes to be positioned in substantially the same relation lengthwise of the shoe to said sole-pressing means, and means for varying the adjusted positions of said toe and heel-end supports in accordance with variations in length of shoes of different sizes.

18. In a machine for pressing soles on the bottoms of shoes, the combination with sole pressing means, of means for supporting a shoe and its last at the forepart and the heel end for the sole pressing operation comprising toe and heel-end supports movable lengthwise of the shoe to accommodate shoes of different sizes, means for positioning shoes of different sizes in substantially the same relation lengthwise of the shoe to said sole pressing means comprising a device for engaging the toe end of the shoe and a heel-end engaging member, means for moving said device and member into engagement with the toe end and the heel end of each shoe, and connections between said toe-end engaging device and said supports for moving the supports into positions to engage each shoe and last in substantially the same relation lengthwise of the shoe.

19. In a machine for pressing soles on the bottoms of shoes, the combination with sole pressing means, of means for supporting a shoe and its last at the forepart and the heel end for the pressing operation comprising toe and heel-end supports adjustable lengthwise of the shoe to accommodate shoes of different sizes, devices movable toward each other lengthwise of the shoe to clamp each last and shoe and to position them in substantially the same relation lengthwise of the shoe to said sole pressing means, and a lever swingable in response to such movement of said devices for adjusting the toe and heel-end supports.

20. In a machine for pressing soles on the bottoms of shoes, the combination with sole pressing means, of means for supporting a shoe and its last at the forepart and the heel end for the sole pressing operation comprising toe and heel-end supports, means for positioning shoes of different sizes in substantially the same relation lengthwise of the shoe to said sole pressing means comprising devices for engaging each shoe at its toe and heel ends, and mechanism for moving said devices into shoe engaging positions and

for varying the relative heightwise positions of said supports in accordance with variations in thickness between the foreparts and the heel ends of lasts of different sizes to cause each last to be positioned with its bottom face at the toe and heel ends at substantially the same height irrespective of the size of the last.

21. In a machine for pressing soles on the bottoms of shoes, the combination with sole pressing means, of means for supporting a shoe and its last at the forepart and the heel end for the sole pressing operation comprising toe and heel-end supports, a holder on which said supports are mounted to swing heightwise of the shoe about an axis extending laterally of the shoe, devices for positioning shoes of different sizes in substantially the same relation lengthwise of the shoe to said sole pressing means by engagement with the toe end and the heel end of each shoe, mechanism for moving said devices into shoe engaging positions, and mechanism for imparting to said toe and heel-end supports in response to such movement of said devices swinging movements of different extent relatively to said holder for shoes of different sizes, said mechanism being constructed to vary the relative heightwise positions of said toe and heel-end supports in accordance with variations in thickness between the foreparts and the heel ends of lasts of different sizes to cause each last to be positioned with its bottom face at the toe and heel ends in substantially the same heightwise relation to said sole pressing means.

22. In a machine for pressing soles on the bottoms of shoes, the combination with sole pressing means, of means for supporting a shoe and its last at the forepart and the heel end for the sole pressing operation comprising toe and heel-end supports, a bar on which said supports are mounted for adjustment lengthwise of the shoe to accommodate shoes of different sizes, a holder to which said bar is pivotally connected for swinging movements about an axis extending laterally of the shoe and located adjacent to the toe end of the shoe, and mechanism for positioning shoes of different sizes in substantially the same relation lengthwise of the shoe to said sole pressing means and for imparting to said bar swinging movements of different extent relatively to said holder for shoes of different lengths to vary the relative heightwise positions of said toe and heel-end supports in accordance with variations in thickness between the foreparts and the heel ends of lasts of different sizes.

23. In a machine for pressing soles on the bottoms of shoes, the combination with sole pressing means, of means for supporting a shoe and its last at the forepart and the heel end for the pressing operation comprising toe and heel-end supports, a bar on which said supports are mounted for adjustment lengthwise of the shoe, a holder to which said bar is pivotally connected for swinging movements about an axis extending laterally of the shoe and located adjacent to the toe end of the shoe, devices connected together for movement toward each other lengthwise of the shoe for positioning shoes of different sizes in substantially the same relation to said sole pressing means by engagement with the toe and heel ends of each shoe, a slide connected to one of said devices and movable lengthwise of the shoe into different positions for shoes of different sizes, said slide having an inclined bar engaging face arranged to cause swinging movements of different extent to be imparted

- to said bar by the movement of said slide into different positions for shoes of different sizes to vary the relative heightwise positions of said supports in accordance with variations in thickness between the foreparts and the heel ends of lasts of different sizes.
24. In a machine for pressing soles on the bottoms of shoes, the combination with means for supporting a shoe and its last for the sole pressing operation, of sole pressing means comprising a flexible pad for engaging the forepart, shank and heel-end portions of the sole of a shoe on said supporting means, means for effecting relative movement of the supporting means and the pad to bring the sole of the shoe into engagement with said pad and then to press the shoe and sole together, and separate means acting through the pad in response to said relative movement to apply different pressures to the entire forepart and shank portions respectively of the sole, said separate means being also adjustable independently of each other to vary relatively the pressures applied to the forepart and shank portions of the sole.
25. In a machine for pressing soles on the bottoms of shoes, a flexible sole pressing pad shaped to conform substantially to the contour of the bottom of a shoe from its toe to its heel end, a flexible container for supporting said pad, said container having a plurality of separate fluid-filled chambers for engaging respectively the forepart and shank portions of said pressing pad, means for pressing a shoe and sole against said flexible pad, and separate means acting through said fluid-filled chambers to cause the pad to apply the forepart and shank pressures to different portions of the sole.
26. In a machine for pressing soles on the bottoms of shoes, a flexible sole engaging pad shaped to conform substantially to the contour of the bottom of a shoe from its toe to its heel end, a flexible container for supporting said pad, said container having fluid-filled chambers separated by a rib extending laterally of the shoe and located substantially at the junction of the forepart and shank pressing portions of said pad, means for pressing a shoe and sole against said pad, and separate means acting through said fluid-filled chambers to cause the pad to apply greater pressure to the shank portion of the sole than to the forepart.
27. In a machine for pressing soles on the bottoms of shoes, a flexible sole engaging pad, a flexible container for supporting said pad, said
- 5 5 10 15 20 25 30 35 40 45 50
- container having a plurality of separate fluid-filled chambers, means for pressing a shoe and sole against said pad, confining means for said flexible container constructed and arranged to expose a portion of one wall of each of said fluid-filled chambers, a plunger for engaging the exposed portion of the wall of each of said chambers, and separate spring means acting on said plungers to apply different pressures through said fluid-filled chambers to different portions of said flexible pad in the sole pressing operation.
28. In a machine for pressing soles on the bottoms of shoes, shoe and last supporting means, sole pressing means comprising a flexible rubber pad, a flexible container for supporting said pad, said container having a plurality of fluid-filled chambers, confining means for said container comprising a cover plate having a plurality of recesses therein for exposing a portion of one wall of each of said chambers, means for moving the supporting means relatively to said pressing means to press the sole of a shoe on said supporting means against said pad, plungers slidably mounted in said recesses for engaging the exposed portions of the walls of said chambers, and separate spring means for exerting different pressures through said plungers on the exposed portions of the walls of said fluid-filled chambers to cause the sole pressing pad to apply different pressures to different portions of the sole.
29. In a machine for pressing soles on the bottoms of shoes, shoe and last supporting means, sole pressing means comprising a flexible rubber pad shaped to conform substantially to the contour of the bottom of a shoe from its toe to its heel end, a flexible container for supporting said pad, said container having fluid-filled chambers separated by a wall extending laterally of the pad and located substantially at the junction of its forepart and shank pressing portions, confining means for said container comprising a cover plate having recesses formed therein to expose a portion of one wall of each of said chambers, means for moving said supporting means relatively to said pad to press the sole of a shoe on said supporting means against the pad, plungers slidably mounted in said recesses for engaging the exposed portions of the walls of said chambers, and separate spring means acting on said plungers to apply different pressures through said fluid-filled chambers to the forepart and shank pressing portions of said pad in the sole pressing operation.
